ALEXANDER BROOKS STEVENS, OF OAKLAND, CALIFORNIA, ASSIGNOR TO SCHMIDT LITHOGRAPH COMPANY, OF SAN FRANCISCO, CALIFORNIA, A CORPORATION OF CALIFORNIA.

PACKAGE DISPLAY EASEL.

Application filed May 27, 1924. Serial No. 716,219.

This invention relates to a package display easel which is capable of producing a raised supporting floor for many different sizes of packages with advertising matter 5 at the back and sides of the package thereby greatly improving the selling effect of the easel.

This particular easel is so constructed that it has many advantages over other easels 10 in that the package support can be easily enlarged to take almost any kind of a package and the package support can be made very strong with a very light quality of board.

15 Another object of this invention is to provide an easel with displays in several planes to produce a pleasing effect as a whole.

Another object of the invention is to provide means whereby the side panels are effectively held in a given position.

Another object of the invention is to provide a support for the package which may be increased or diminished in strength depending on how much may be needed for the 25 given display.

Fig. 1 is a front view of the easel, a package being shown thereon in dotted lines.

Fig. 2 is an edge view of the easel.

Fig. 3 is a plan view of the easel.

30 Fig. 4 is a plan view of the blank forming the easel unfolded.

Fig. 5 is a front elevation of an easel of a slightly modified construction in which an extra supporting panel is used for the floor 35 on which the objects for sale are placed.

Fig. 6 is an edge elevation of the same easel.

Fig. 7 is a plan view of the same easel, and Fig. 8 is a plan view of the unfolded cut 40 blank from which the easel is set up.

The easel blank is cut and scored to produce the panels and locking tabs numbered from 1 to 18.

Of these parts 1 and 18 represent two display cards at the ends or sides of the package, 10 represents the back display card. The package display floor 9 is rectangular and is supported by the panels, 5, 6, 8, 13 and 14, the panels 6 and 14 being locked to the 45 panels 5 and 13 by passing the hooks, and 50 panels 5 and 13 also have slots 21, 22 to re-

ceive the locking tabs 4 and 12 depending from the panels 3 and 11. In order to more satisfactorily hold the panels 1 and 18 in 55 position, they have the bottom flaps 2 and 17, which rest on the top of the counter; each with one end projecting under the panels, forming the stand for the article to be displayed. This causes the side panels to be 60 held erect by the weight of the article to be displayed better than they would be if no such holding flap was used.

It will also be seen that when the easel is set up that the two members 3 and 11 65 form a sort of end enclosure for the object being displayed and they are held in position by the tabs 4 and 12 which pass through the slots 21 and 22.

If a stand for a very heavy object is 70 desired, the same pattern may be used with the added flap shown in Figs. 5 to 8. In this figure the numbers 1 to 22 are applied to the same parts as in the preceding figures but there is the additional panel 23 on the 75 edge of the shelf 9 and there is the addition 10 to the back panel 10, so it will reach the floor on which the easel is placed.

Whichever way this easel is made, a very solid support for the object is produced and 80 the reading surfaces are very substantially held in the desired position. This easel may be shipped perfectly flat and requires no glue to set it up or hold it after being set up.

What I claim is as follows, but modifications may be made in carrying out the invention described above within the purview of the annexed claim.

A package display easel comprising a raised floor adapted to receive a package, 90 and supported by end and side panels forming an inverted box like structure, a back vertical display card hinged to the back of said floor by two hinged panels, said panels when folded down adapted to form a support for the rear of said floor, vertical side display cards on each side of said floor, panels connecting said side cards to said back cards, and means for locking said floor and display cards in display position. 95

In testimony whereof I have hereunto set my hand this 17th day of May A. D. 1924.

ALEXANDER BROOKS STEVENS.
